[57] CLAIM

The ornamental design for a side rail for rolling gates, substantially as shown.

DESCRIPTION

FIG. 1 is a perspective view taken from the top, front and left side of a side rail for rolling gates, showing my new design;

FIG. 2 is a perspective view taken from the bottom, rear and right side thereof; and

FIG. 3 is a left side elevational view thereof.

FIG. 1

FIG. 2

FIG. 3
